(57) **CLAIM**

The ornamental design for a floor lamp, as shown and described.

DESCRIPTION

FIG. 1 is a perspective view of a floor lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the floor lamp shown in an alternative use position.

The broken lines in the drawings depict portions of the floor lamp that forms no part of the claimed design.

1 Claim, 8 Drawing Sheets
